UNITED STATES PATENT OFFICE

2,627,254

FUEL INJECTION NOZZLE

Kalman J. De Juhasz, State College, Pa., assignor
to The Texas Company, New York, N. Y., a corporation of Delaware

Application June 12, 1947, Serial No. 754,099

1 Claim. (Cl. 123—32)

1

This invention relates to a fuel injection nozzle for an internal combustion engine, and particularly to a nozzle of the type producing a pilot jet at one side of and slightly preceding a main jet during the injection period.

A principal object of the invention is to provide an improved fuel injection nozzle of this type wherein the pilot injection orifice is an open hole orifice independent of the main orifice and needle valve, whereby each orifice can be independently designed to produce a different controlled type of spray or jet.

Another object of the invention is to provide a fuel injection nozzle constructed to produce a preceding non-flaring directional pilot jet designed to facilitate prompt spark ignition, and a closely following flaring main jet alongside of the pilot jet designed for uniform air impregnation, the two jets functioning to promote rapid formation of the flame front and efficient combustion in a non-knocking combustion cycle.

Still another object of the invention is to provide a fuel injection nozzle of this type, together with a fuel pump having a delivery valve with cylindrical cuff below the seat of the delivery valve to compensate for fuel back-flow at the end of each injection period from both the needle valve closing space and also the open hole orifice to thereby prevent dribbling of fuel from the nozzle tip.

Other objects and advantages of the present invention will be apparent from the following description when taken in conjunction with the attached drawing and appended claims.

The fuel injection nozzle of the present invention is particularly designed for use in connection with the internal combustion engine and method of operating the same with non-knocking combustion disclosed and claimed in the pending application of Everett M. Barber, Serial No. 742,275, filed April 18, 1947, now Patent No. 2,595,915, dated May 6, 1952. In accordance with said application, injection of fuel into rapidly swirling compressed air is initiated toward the latter part of the compression stroke by a pilot jet which is directed across a small chord of the combustion space in the direction of air swirl and adjacent to the periphery of the combustion space. The resulting fuel vapor-air mixture formed from the first increment of injected fuel of said pilot jet is immediately spark ignited to establish a flame. The pilot jet is closely followed by a flaring main jet which is directed alongside of the pilot jet so as to uniformly impregnate the compressed air at one

5 side of the combustion space as it swirls past the locus of injection. The lag between the pilot jet and the main jet is just sufficient so that the leading edge of the main jet in combustible mixture form reaches the locus of ignition just after the formation of a flame from the pilot jet, so that the flame rapidly spreads across the leading edge of the main jet to establish a flame front across said one side of the combustion space, thereby avoiding the bypassing of any substantial quantity of unburned combustible mixture beyond the locus of the flame front before the latter can be established. Injection is then continued immediately upstream of the flame front to develop the power required on each cycle and in a manner such that additional portions of combustible fuel vapor-air mixture are progressively formed and burned substantially as rapidly as produced, with the result that knocking of the engine is not possible.

20 A known type of fuel injection nozzle designed to produce a preceding pilot jet at one side of a closely following and flaring main jet comprises a single orifice nozzle tip having a conical valve seat in the fuel passage leading to the injection orifice and controlled by the usual pintle valve opening under the influence of fuel under injection pressure, together with a small groove or channel formed in one side of the conical valve seat. Upon the application of fuel under injection pressure, a small stream of fuel first passes through this channel or groove and escapes through the single injection orifice in the form of a small jet directed at an angle 25 according to the inclination of the conical valve seat; and then the pintle valve lifts to produce the main flaring jet in a direction generally parallel to the longitudinal axis of the nozzle and pintle valve.

30 While this type of nozzle can be employed in carrying out the method of said prior application, certain practical difficulties are presented, particularly in the design of the nozzle tip and conical seat with groove, in order to attain the proper directions and configurations of the respective pilot and main jets. Moreover, in said prior design, with the pintle valve lifted, the directional force of the pilot jet is largely destroyed, with the result that the two jets merge 35 into a single flaring jet which has a tendency to shift slightly from the initial location of the pilot jet.

35 In accordance with the present invention, these difficulties are overcome by providing an injection nozzle having a tip formed with both an

open hole pilot orifice communicating directly with the fuel pressure chamber upstream of the needle valve seat, and with a separate main injection orifice controlled in the customary manner by the needle valve. In this way, the open hole pilot orifice is made entirely independent of the main orifice and needle valve; and each orifice can be independently designed as to angular inclination, length to diameter ratio, and size or diameter, to produce a preceding pilot jet closely followed by a main jet, each of the desired spray configuration, penetration and location. Preferably, in accordance with the present invention, the main orifice controlled by the needle valve is of larger diameter and has a smaller length to diameter ratio as well as angular inclination; while the pilot orifice is of smaller diameter and has greater length to diameter ratio and greater angular inclination.

Further, the present invention provides a fuel injection nozzle of this improved type in conjunction with a fuel pump having a delivery valve provided with an enlarged cuff to compensate for fuel back-flow from both the pintle valve closing space and also the open hole orifice at the end of each injection period, to prevent dribbling of fuel from the nozzle tip.

The invention is more particularly illustrated in the attached drawing which discloses a preferred embodiment thereof and wherein:

Fig. 1 is a vertical sectional view through a fuel injection nozzle constructed in accordance with the present invention;

Fig. 2 is an enlarged vertical sectional view through a portion of the nozzle tip and associated needle valve of Fig. 1;

Fig. 3 is a partial vertical sectional view through the delivery valve assembly and associated mechanism of a fuel pump employed in conjunction with the fuel injection nozzle of the present invention; and

Fig. 4 is a diagrammatic view, partly in elevation and partly in section, illustrating the application of the present invention to a cylinder of an internal combustion engine and the operation taking place in the combustion space of said cylinder.

Referring particularly to Fig. 1, the fuel injection nozzle comprises a body member 10 having a side boss 11 which threadedly receives a coupling 12 to which the fuel line 13 (Fig. 4) is connected. Boss 11 is drilled to provide a fuel channel 14 which communicates at its inner end with a downwardly extending fuel channel 15 drilled in the body member 10.

The nozzle also comprises a tip member 17 held in engagement with the lower end of body member 10 by a coupling 18 threadedly received by exterior threads on the body member and engaging a shoulder 19 on tip member 17. The upper surface of the body portion of tip member 17 is formed with an annular groove 20 which registers with the lower end of fuel channel 15. Said groove 20 communicates in turn with a fuel passage 21 drilled in the body portion of the tip member.

Referring more particularly to Fig. 2, the tip member is formed with an enlarged fuel pressure chamber 23 communicating with the lower end of fuel passage 21. Tip member 17 is also provided with an axial bore 24 slidably receiving a needle valve 25. At the lower end of pressure chamber 23, the tip member is formed with a tip portion having a conical valve seat 26 adapted to cooperate with a conical seating surface

27 formed on needle valve 25. Beyond the valve seat 26, the tip portion is formed with a smaller diameter extension 28 containing a fuel passage 29 which communicates with the main spray orifice 30 drilled through the extension 28. Drilled through the tip portion at one side of extension 28 is a pilot orifice 31 which communicates directly with the fuel pressure chamber 23 upstream of the needle valve seat, and thus constitutes an open hole orifice. Preferably the body portion and the tip portion of the tip member are integral as shown; although they may be formed in two parts to provide for exchangeable tips. This tip member with associated needle valve is termed herein a "nozzle tip assembly" irrespective of whether or not the tip member is formed in one or more parts.

Again referring to Fig. 1, body member 10 is also formed with an axial bore slidably receiving a stem 34 which bears at its lower end in loose fitting engagement with the upper end of a pin 35 carried by needle valve 25. The upper end of a body member 10 is cup-shaped to receive a spring retainer 37 bearing on the upper end of stem 34, and a compression spring 38 whose lower flattened end engages a shoulder of spring retainer 37. An enlarged bore at the extreme upper end of the cup portion of body member 10 is interiorly threaded to receive a sleeve member 39 which surrounds the upper end of compression spring 38. The upper end of sleeve member 39 has an interiorly threaded bore which receives the compression adjusting member 40 bearing at its lower end against upper spring retainer 41, which in turn bears against the upper flattened end of compression spring 38. The upper end of adjusting member 40 is formed with a slot 42 for the reception of a screwdriver, by means of which the member 40 can be threaded in or out to adjust the compression in spring 38. The parts are locked in adjusted position by a nut 43 threaded on member 40 and seating against the upper surface of sleeve 39. The entire upper assembly is enclosed by a cover cap 44 which is threadedly received by exterior threads on sleeve 39 and is adapted to seat against the upper surface of body member 10. The opening movement of needle valve 25, in response to fuel pressure in chamber 23 acting on the conical surface 46 of the valve, is limited by engagement of the upper end of needle 25 with a shoulder 47 at the lower end of body member 10.

Body member 10 also threadedly receives a leakage coupling 50 connected to a return line 51 (Fig. 4) which functions to return any fuel leakage past the pintle valve to the source of supply.

Referring again to Fig. 2, it will be noted that the main spray orifice 30 is of comparatively large diameter and has a comparatively small length to diameter ratio generally of the order of about 2:1 to 5:1. Moreover, this main spray orifice extends at a relatively smaller angle indicated by the arrows 52 to the longitudinal axis of the nozzle tip and needle valve. On the other hand, the pilot orifice is of comparatively small diameter and has a relatively large length to diameter ratio of the order of about 10:1 to 20:1. The predetermined length to diameter ratio of this orifice is conveniently fabricated by milling the peripheral part of the tip portion at an angle as shown at 55 and also by counter-sinking of the outer end of the tip member opposite the orifice 31 as indicated at 53. Also this pilot

orifice 31 has a relatively large angular inclination indicated by the arrows 54 with respect to the longitudinal axis of the nozzle tip and needle valve. While the construction shown, with extension 28 containing an angular main orifice 39 of comparatively small length to diameter ratio, constitutes a preferred arrangement, it is to be understood that the main flaring spray can be formed in any suitable manner. Thus a pintle valve can control the discharge of a solid jet against the side wall of an outwardly flaring and angularly arranged spray passage in the tip, so that the main spray is deflected into the combustion space as a flaring jet with proper angular inclination. The construction shown is preferred due to better reproducability of the desired configuration and location of the main spray on succeeding cycles. Moreover, it will be understood that a spiral insert can be mounted in the fuel passage 29 to give the fuel a swirling movement as it passes to and through the main spray orifice 30. Wherever the expression "needle valve" is used in the claims, it is to be understood that this generically covers the various constructions described above, including a simple shut-off valve for an orifice controlling the rate of fuel discharge, as well as a pintle valve wherein the pintle cooperates with the fuel passage or valve seat in controlling the rate of discharge.

The manner in which the fuel injection nozzle is mounted in the engine cylinder is illustrated in Fig. 4. The cylinder indicated diagrammatically at 53 is formed with a bore within which the nozzle is clamped by the customary bolts not shown. This bore may extend at an angle to a radius of the cylinder as illustrated, so that the nozzle is set somewhat tangentially of the combustion space indicated at 57; or the bore may extend radially of the cylinder, and additional angular inclination as indicated by the arrows 52 and 54 in Fig. 2 given to the orifices 39 and 31, respectively. The nozzle is mounted with the tip 17 barely protruding through the cylinder wall into the periphery of the combustion space, and so that the orifices 31 and 39 are positioned on the air downstream side to produce the jets 58 and 59, respectively. As indicated, the pilot jet 58 is directed across a small chord of the combustion space adjacent the periphery thereof, and so as to just miss the electrodes 60 of a spark plug 61 mounted in the wall of the cylinder adjacent to the nozzle, generally about 20-60° from the nozzle as formed by radii passing through the locus of injection and the locus of ignition respectively. The main jet 59 is directed more toward the center of the combustion space and alongside the pilot jet 58 at one side of the combustion space.

As previously explained, the pilot orifice 31 is constructed with relatively small diameter and relatively large length to diameter ratio in order to produce a non-flaring or pencil type of jet which can be accurately designed with respect to penetration and angular inclination to facilitate prompt spark ignition of the first entering portion of fuel from said jet as soon as combustible fuel vapor-air mixture is formed therefrom. The jet 58 just misses the electrodes 60, while combustible mixture diffusing from the edge thereof into the small recess 62 in the cylinder wall contacts electrodes 60 for prompt spark ignition. The main orifice 39 on the other hand is constructed of relatively large diameter and relatively small length to diameter ratio to produce a flaring jet 59 whose main function is to

uniformly impregnate the compressed swirling air on one side of the combustion space 57 as it rotates past the locus of fuel injection. It will be understood that the cylinder is provided with air intake means, such as an inlet valve with shroud set tangentially, to impart a high velocity of swirling movement to the air as it is introduced into the combustion space 57, which swirling movement is maintained during the compression stroke of the engine piston, as indicated by arrow 63.

Fuel is supplied to fuel line 13 by fuel pump 65 having a fuel pump plunger 66 reciprocated by cam 67 carried by cam shaft 68 driven from the engine at one-half engine speed for four cycle operation. Pump plunger 66 forces fuel under injection pressure from the plunger chamber 70 past delivery valve 71 opposed by spring 72 into the delivery chamber 73 formed in fitting 74. The latter is connected by union nut 75 with the fuel line 13. It will be understood that the fuel pump is of the conventional type wherein the plunger 66 on its upward or pumping stroke forces fuel under injection pressure into delivery chamber 73 and then through fuel line 13 to the nozzle for a predetermined portion of its pumping stroke as determined by load, and then opens communication between the plunger chamber 70 with a spill port (not shown) to immediately release the injection pressure within the fuel line and allow needle valve 25 and delivery valve 71 to come to their seats thus terminating injection.

In accordance with the present invention, delivery valve 71 is formed with a cylindrical cuff 77 which is slidably received within the surrounding bore of check valve holder 78. On opening movement of delivery valve 71, the latter rises until the cuff 77 moves completely out of the bore of holder 78, thus permitting fuel to pass from plunger chamber 70 into delivery chamber 73. This movement reduces the effective fuel volume of delivery chamber 73 by an amount equivalent to the volume displaced by cuff 77. Conversely, when delivery valve 71 returns to its seat at the termination of injection, movement of cuff 77 from chamber 73 back into the bore of holder 78 increases the effective fuel volume of delivery chamber 73 by that amount.

The length and diameter of cuff 77 is so selected in accordance with the present invention as to compensate for back-flow of fuel resulting from both the closing of needle valve 25, which reduces the effective volume of fuel pressure chamber 23, and also back-flow of fuel from the open hole orifice 31. It will be appreciated that when the injection pressure in fuel line 13 is released at the termination of the injection period, the pressure within the combustion space 57 during the immediately succeeding portion of the combustion stroke will exceed the fuel pressure within chamber 23, the connecting passages 21, 15 and 14, and fuel line 13. Consequently, sufficient back-flow of fuel is permitted by the closing movement of delivery valve 71 to drain pilot orifice 31 back into chamber 23, which avoids dribbling of fuel from this open hole orifice. Since the delivery valve 71 then remains on its seat until the succeeding injection period, flow of fuel from chamber 23 through open hole orifice 31 is impeded throughout the balance of the cycle, including the suction stroke of the engine piston, thereby preventing the escape of fuel from this orifice until the succeeding injection period.

In operation, air is drawn into the combustion

space 57 of the engine cylinder 56 on the suction stroke of the piston in a manner to produce a high velocity swirling movement therein. This air is compressed on the compression stroke while the high velocity swirling movement is maintained. Generally about 75 to 30° before top dead center of the piston, injection of fuel is initiated under the control of pump plunger 66, which forces fuel under injection pressure, thus opening delivery valve 71, into delivery chamber 73, fuel line 13 and the injection nozzle. This injection pressure is thus communicated to fuel pressure chamber 23, thereby producing immediate injection of pilot jet 58 through the open hole orifice 31. The first increment of injected fuel of pilot jet 58 is spark ignited at electrodes 60 of plug 61 substantially as soon as combustible mixture is formed therefrom to establish a flame. Promptly following the beginning of injection of pilot jet 58, the increasing pressure of fuel in chamber 23 caused by the continuing motion of plunger 66, acting on conical surface 46 of needle valve 25, opens the latter and initiates injection of the main flaring spray 59. The leg between the start of pilot injection is just sufficient so that the leading edge of the first increment of injected fuel of the main spray 59 has barely reached the locus of ignition at the time a flame has been established by spark ignition of the pilot jet 58. This flame rapidly sweeps across the leading edge of the main spray 59, thereby establishing a flame front extending generally across a radius of the combustion space. Thereafter, injection of fuel is continued from both the pilot jet 58 and the main jet 59 immediately in advance of the established flame front, so that additional portions of combustible fuel vapor-air mixture are progressively formed and burned substantially as rapidly as formed, whereby knocking of the engine is prevented.

Injection is continued on each cycle to develop the power required, which for full load may be for a duration of about 40-75 crank-angle degrees or sufficient to substantially completely impregnate the mass of compressed swirling air within the combustion space on one complete rotation thereof. Injection is then terminated by releasing the injection pressure within the fuel line, causing the needle valve 25 to slam shut on its seat, and also resulting in the closing of delivery valve 71. Movement of cylindrical cuff 77 back into holder 78 prevents dribbling of fuel from the open hole orifice 31, while closing of needle valve 25 prevents dribbling from the main orifice 30. The power stroke of the piston is completed and the exhaust stroke takes place in the customary manner; when the cycle is then repeated.

By way of example of the present invention, the main spray orifice 30 may have a diameter of .014 inch with a length to diameter ratio of 2:1, and an angular inclination of 30°. The pilot orifice 31 may have a diameter of .006 inch and is countersunk sufficiently to provide a length to diameter ratio of 16:1, with an angular inclination of 45°. The nozzle is mounted partially tangentially so that the longitudinal axis of the nozzle makes an angle of about 20° with the radius extending through the nozzle tip; and the spark plug 61 is mounted at a radial angle of 45° from the locus of injection in the direction of air swirl.

While the present invention has been particularly described above as applied to an engine operating with the non-knocking combus-

tion, it is to be understood that the pilot injection nozzle disclosed herein is of more general application to fuel injection engines, such as diesel engines, as well as spark ignition engines operating on the Otto cycle.

Obviously, many modifications and variations of the invention as hereinbefore set forth may be made without departing from the spirit and scope thereof, and therefore only such limitations should be imposed as are indicated in the appended claims.

What I claim is:

In an internal combustion engine, the combination with a cylinder, of a fuel injection nozzle mounted through said cylinder wall with the tip thereof adjacent the periphery of the cylinder combustion space, said nozzle provided with a tip assembly having a body portion with a fuel supply passage and a tip portion, said parts enclosing a fuel pressure chamber in open communication with said fuel supply passage, a valve seat formed at the inner side of said fuel pressure chamber, a spring loaded outwardly opening needle valve normally in engagement with said valve seat, means for supplying fuel under injection pressure to said fuel supply passage and pressure chamber during the fuel injection period of each cycle and for then releasing said pressure to terminate injection, said spring loading being such that the injection pressure of fuel in said pressure chamber during each fuel injection period is sufficient to overcome the spring loading to open said needle valve throughout the entire load range of said engine, said tip portion having a bulbous extension beyond said valve seat and valve containing a fuel passage and a main injection orifice extending through the wall of said bulbous extension at one side thereof to communicate with said last mentioned fuel passage, said tip portion also having an open hole pilot injection orifice extending through the wall of said tip portion outwardly of said bulbous extension and valve seat to communicate directly with said pressure chamber, said pilot injection orifice being located on the same side of said tip member as said main orifice and so that both orifices lie substantially in the same plane of a cross-section taken through the tip member along the longitudinal axis thereof, said pilot orifice having a relatively small diameter, a relatively large length to diameter ratio, and a relatively large angular inclination to the longitudinal axis of the nozzle tip and needle valve adapted to provide a thin pencil-like pilot jet directed across a small chord of the combustion space adjacent the periphery thereof, and said main orifice having a relatively large diameter, a relatively small length to diameter ratio, and a relatively small angular inclination to the longitudinal axis of the nozzle tip and needle valve adapted to provide a flaring main jet alongside of the pilot jet which substantially encompasses the balance of the space across a radius of the combustion space between the pilot jet and the center of the combustion space, and an inwardly opening delivery check valve connected to said fuel supply passage, said delivery check valve having a cuff of sufficient volume to compensate for fuel backflow from both said needle valve closing space and said open hole orifice at the end of each injection period to prevent dribbling of fuel from said nozzle tip.
